UNITED STATES PATENT OFFICE.

ATWELL AUSTIN, OF PAWNEE, OKLAHOMA, ASSIGNOR OF ONE-HALF TO HENRY JACKSON, OF PAWNEE COUNTY, OKLAHOMA.

JOURNAL-BOX.

1,070,317.

Specification of Letters Patent. Patented Aug. 12, 1913.

Application filed November 25, 1911. Serial No. 662,421.

To all whom it may concern:

Be it known that I, ATWELL AUSTIN, a citizen of the United States of America, residing at Pawnee, in the county of Pawnee, and State of Oklahoma, have invented new and useful Improvements in Journal-Boxes, of which the following is a specification.

The invention relates to improvements in journal boxes and has particular application 10 to journal boxes for car wheels.

One object of the invention is the provision of a journal box adapted to contain oil or other suitable lubricating material, which shall be provided with means to prevent 15 leakage of the oil therefrom.

A further object of the present invention is to provide a journal box capable of containing a quantity of lubricating material and applicable to the journals of car wheels, 20 the journal box and the journal of the car wheel being provided with companion elements which cooperate with each other to prevent the leakage of oil from the journal box.

25 With the above and other objects in view the invention resides in the construction, combination and arrangement of parts hereinafter described and pointed out with particularly in the appended claim.

30 In the accompanying drawings forming a portion of this specification; Figure 1 is a side elevation of a journal box constructed in accordance with the present invention and applied to a car wheel. Fig. 2 is a longitudinal sectional view through the journal box, 35 and Fig. 3 is a transverse section through the same.

Referring more particularly to the accompanying drawings, in which I have illustrated the preferred embodiment of the invention, 1 designates a car wheel constructed of any suitable or preferred material and provided with the usual journal 2.

The journal box is designated at 3 and 45 comprises sections 4 and 5, each of which is formed with laterally projecting longitudinal flanges 6 and 7 respectively provided with alining openings designed to receive bolts 8 to secure the sections in box-forming 50 position. Pivottally connected to the forward end of the section 4 is a door or lid 9 designed to engage the inclined front wall 10 of the lower section 5 to close the box, the section 5 being adapted to contain a sufficient 55 quantity of oil or other lubricating fluid.

The rear ends of the sections 4 and 5 of the journal box are preferably inturned to provide inwardly extending flanges 11 and 12 respectively, each of which is formed with a semicircular opening designed to coöperate 60 with one another in the assembling of the sections of the journal box to form an opening 13 of a diameter slightly greater than the similar dimension of the journal 2 of the car wheel thereby eliminating friction between the rear walls of the journal box and the car wheel journal.

Interiorly of the journal box, the flanges 11 and 12 are provided with companion segments 14 and 15 respectively adapted to co- 70 operate with one another to form a ring-like member, each of the said segments of the ring-like member being provided with alining outturned flanges 16, the purpose of which will presently appear.

Rigidly secured to the journal 2 upon the interior of the journal box and adjacent the opening 13 therein, is a disk 17 provided with a peripheral flange 18 terminating in an inwardly projecting annular lip 19 80 adapted to snugly engage the flanges 16 of the ring-like member to prevent the escape of oil from the journal box through the opening 13, the disk 17 being rotatable with the journal 2 of the car wheel and relatively 85 to the ring-like member formed by the companion sections 14 and 15. This disk is preferably formed of a number of sections so that the same may be applied to the axle of the wheel and interlocked with the segments 14 and 15, the sections of the disk being fastened to each other in disk formation through the medium of bolts and flanges, of a band surrounding the flange 18.

From this construction it will be seen that 95 leakage of the oil from the journal box, through the opening 13 therein, is prevented thereby obviating the waste incident, heretofore, in journal box construction.

From the foregoing description, taken in 100 connection with the accompanying drawing, the advantages of the construction and of the method of operation will be readily apparent to those skilled in the art to which the invention appertains, and while I have described 105 the principle of operation of the invention, together with the device which I now consider to be the best embodiment thereof, I desire to have it understood that the device shown is merely illustrative, and that such 110

changes may be made when desired as are within the scope of the claim appended hereto.

Having thus described my invention what 5 I claim and desire to secure by Letters-Patent is:

The combination with a car wheel journal, of a journal box comprising two sections each carrying a segment cooperating with 10 the companion segment to form a ring-like member and provided with an outturned flange alining with the flange on the adjacent segment, a disk rigidly secured to the said car wheel journal within the journal box and

formed with a peripheral flange having an 15 annular lip projecting inwardly thereof and spaced apart from the disk and adapted to snugly engage the flanges of the ring-like member on the companion segments on the sections of the journal box whereby leakage 20 of the lubricating material from the journal box is avoided.

In testimony whereof I affix my signature in presence of two witnesses.

ATWELL AUSTIN.
